WEFT-DETECTING MECHANISM.

1,142,121.

Specification of Letters Patent. Patented June 8, 1915.

Application filed September 16, 1914. Serial No. 862,101.

To all whom it may concern:

Be it known that I, EPPA H. RYON, a citizen of the United States, residing at Waltham, in the county of Middlesex and State of Massachusetts, have invented a new and useful Weft-Detecting Mechanism, of which the following is a specification.

This invention relates to a weft detecting mechanism and particularly to a detecting mechanism of the pneumatic type. Such mechanism has been heretofore known but has usually operated upon a pressure system in which the weft replenishing devices have been maintained inoperative until the pressure in the pneumatic devices was reduced by the opening of an exhaust valve. Apparatus of this type, while capable of very sensitive operation, is dependent for its operation upon the maintenance of pressure higher than atmospheric. If for any reason this pressure is not maintained, the whole device becomes inoperative. Furthermore, the number of working parts to the loom is materially increased by the addition of the necessary air compressing apparatus.

It is the principal object of my present invention to provide an improved pneumatic weft detecting or feeler mechanism in which the air pressure never exceeds atmospheric and no auxiliary air compressing apparatus is required.

With this object in view, my invention contemplates the provision of a weft detecting mechanism in which the mechanism is operable to permit the transfer of filling carriers when the pneumatic device is opened to the atmosphere but in which the transfer is prevented as long as the passage from said pneumatic device to the atmosphere is closed during the operation of the feeler.

My invention further consists in certain devices, arrangements and combinations of parts which will be hereinafter described and more specifically pointed out in the appended claims.

A preferred form and a modification are shown in the drawings, in which—

Figure 1 is a front elevation of the preferred form of my invention, showing also certain parts of the weft replenishing and controlling devices; Fig. 2 is a top plan view of the preferred form; in operative relation to a full weft carrier; Fig. 3 is a view similar to Fig. 2 but showing the feeler operating with a substantially exhausted

weft carrier; Figs. 4 and 5 are sectional views taken along the line 4—5 in Fig. 1 and showing parts in positions corresponding to Figs. 2 and 3, respectively; Fig. 6 is an enlarged detail view of the end of the 60 feeler slide; Fig. 7 is a partial side elevation looking in the direction of the arrow 7 in Fig. 1; Figs. 8 and 9 are sectional plan views of a modification, showing the parts in two 65 positions; Fig. 10 is a side elevation of the modification, corresponding in position to Fig. 7, and Fig. 11 is a side view of the slide shown in Fig. 6.

That portion of my improved weft detecting mechanism which co-operates with the 70 weft carrier comprises a feeler slide 10 mounted in a guide 11 secured to the loom frame and normally maintained in rearward position by a spring 12, positioned between a lug 13 on the guide 11 and a projection 14 75 on the slide 10.

A rod 15 of relatively small diameter is 80 slidably mounted in the slide 10, said rod being screw-threaded at its forward end and provided with a detecting point 16 at 85 its rear end. The rod 15 also has secured thereto a collar 17 (Fig. 6) and is surrounded by a coiled spring 18 positioned between the collar 17 and a bearing 19 secured to the slide 10.

A nut 20 is mounted upon the forward 90 threaded end of the rod 15, said nut being provided with notches 21 (Fig. 1) adapted to receive a spring wire 22 mounted upon the slide 10 and movable therewith. By 95 means of the nut 20, the position of the detecting point 16 relatively to the rear end of the slide 10 may be adjusted, said adjustments being maintained by inserting the wire 22 in one of the notches 21. In addition to positioning the detecting point, the nut 20 performs an additional function which will be hereinafter described.

The slide 10 carries at its forward end a laterally projecting disk-shaped member 30 100 (Figs. 1 and 3) having a concave recess in its rear face. This face of the member 30, in the preferred form, is covered by a diaphragm 31 of leather, rubber, or other suitable material. To the outer face of the diaphragm there is secured a U-shaped casting 32 carrying a stud 33 slidable in a fixed bearing 34 mounted upon the loom frame. The casting 32 may be secured to the diaphragm by a screw 35, as shown in Figs. 4 110

and 5, and the disk-shaped member 30 may be recessed as at 36 to provide clearance for the screw. The concave recess in the member 30 is connected by a passage 37 to a 5 short transverse passage 38 concentric with the rod 15. The passage 38 is so positioned that it will be covered and closed by the nut 20 when the nut is forced against the front face of the slide 10 under the influence of 10 the spring 18.

An arm 40 (Fig. 7) mounted upon a short shaft 41 extends upwardly into the path of movement of the casting 32 (see Figs. 4 and 5). The shaft 41 is rotatable in fixed bearings in the loom frame and is surrounded by a coiled spring 42 tending constantly to force the arm 40 rearwardly against the casting 32. At its opposite end the stud 41 carries an arm 43 to which is pivotally connected a sliding rod 44 (Figs. 2 and 3).

The rod 44 is movable into and out of the path of a floating lever 45 pivotally connected to the end of a vertically movable rod 46. At its left-hand end, as viewed in Fig. 25, 1, the lever 45 is connected through a link 46' to a lever 47 positioned to actuate an operating finger 48 which controls the release of the weft carriers in a well known type of weft replenishing mechanism. The 30 rod 44 and the connections by which it controls the weft replenishing mechanism form no part of my present invention and for a fuller description thereof reference is made to Patent No. 1,005,321 issued to E. H. Ryon, 35 October 10, 1911.

For the purpose of this application, it is sufficient to state that when the rod 44 is maintained in the position shown in Fig. 3, the weft replenishing mechanism will be 40 operated, said mechanism remaining inoperative so long as the rod is withdrawn at each alternate forward beat of the lay, as shown in Fig. 2.

Having thus described the construction of 45 the preferred form of my invention, its operation will be readily understood. When the lay is on or near its back center, the slide 10 will be forced rearward by the spring 12, which movement will continue until the casting 32 engages the bearing 34 and the diaphragm 31 is forced into the position shown 50 in Fig. 4. At the same time the detecting point 16 is free to move rearward and the nut 20 is brought into position to cover the 55 passage 38. As the lay moves forward, the ends of the slide 10 and the detecting point 16 engage the filling. If a sufficient amount of filling remains upon the weft carrier, the 60 point 16 will enter the soft filling and will not be forced forward to open the passage 38. The slide 10 then moves forward with the passage 38 closed. As there is no access for air between the member 30 and the diaphragm 31, the diaphragm must follow the 65 movement of the member 30. The dia-

phragm accordingly moves forward with the disk shaped member, and carries the casting 32 with it. The casting 32 is at all times engaged by the arm 40 which is thus partially rotated, turning the stud 41 and withdrawing the rod 44, the parts then occupying the position shown in Figs. 2 and 4.

When the filling upon the weft carrier becomes substantially exhausted, the detecting point 16 engages the barrel of the bobbin and is forced forwardly, relatively to the slide 10, as shown in Fig. 3. This movement of the point 16 and the rod 15, relatively to the slide 10, uncovers the passage 38, thus opening the recess behind the diaphragm 31 to the atmosphere. As the slide 10 moves forwardly, the air rushes in through the passages 38 and 37 and fills the space behind the diaphragm. There is then no force tending to move the casting 32 forward and the arm 40, stud 41 and the rod 44 accordingly remain in the position shown in Figs. 3 and 5. The weft replenishing mechanism is thus permitted to operate to supply a fresh weft carrier to the shuttle. It will thus be seen that no air-compressing devices of any sort are necessary for the operation of my pneumatic feeler, the entire operation being controlled by the opening and closing of the passage 38 by the nut 20.

In Figs. 8, 9 and 10 I have shown a modified form of my invention, the operation, however, being substantially the same. In this form the slide 10 carries a lateral projection 50 having a cylindrical recess in its rear face within which is slidable a piston 51 having a rod 52 extending forward through the projection 50 and engaging the arm 40 previously described.

The recess in the projection 50 is connected by a short passage 53 to a conical recess 54 surrounding the rod 15. Upon its threaded forward end the rod 15 carries a conical plunger 55 maintained in adjusted position thereon by a check nut 56.

An adjustable stud 57 is mounted upon the guide 11 and extends into the open rear side of the piston 51. The stud 57 engages the forward end of the piston and acts to restore it to the position shown in Figs. 8 and 10 as the slide moves rearwardly, the stud also controlling the extreme rearward position of the slide.

The admission of air to the cylinder is controlled by the position of the rod 15 as 110 in the preferred form and the mode of operation is unchanged.

The rearward position of the slide may be conveniently determined by adjusting the stud 57 longitudinally.

Having thus described two forms of my invention, it will be evident that other changes and modifications can be made therein by those skilled in the art without departing from the spirit and scope thereof.

as set forth in the claims, and I do not wish to be limited to the details herein disclosed, but

What I do claim is:—

- 5 1. In a loom, in combination, weft replenishing mechanism, a weft detecting device, and means controlled by said weft detecting device effective to determine the operation of said weft replenishing mechanism, 70
10 said means comprising a normally-collapsed pneumatic device having a passage to the atmosphere, and a member for closing said passage, said member being controlled by said weft detecting device.
- 15 2. In a loom, in combination, weft replenishing mechanism, a weft detecting device, and means controlled by said weft detecting device effective to determine the operation of said weft replenishing mechanism, said 80
20 means comprising a normally-collapsed pneumatic device having a passage to the atmosphere, and a closure for said passage, said closure being directly controlled by said weft detecting device and being moved 85
25 to open said passage when the weft detecting device contacts with a substantially exhausted weft carrier.
3. In a loom, in combination, weft replenishing mechanism, a weft detecting device, 90
30 and means controlled by said weft detecting device effective to determine the operation of said weft replenishing mechanism, said means comprising a normally-collapsed pneumatic device having a passage to the 95
35 atmosphere, and a closure for said passage movable with and controlled by said weft detecting device.
4. In a loom, in combination, weft replenishing mechanism, a weft detecting device, 100
40 comprising a feeler slide and a detecting point, and means controlled by said weft detecting device effective to determine the operation of said weft replenishing mechanism, said means comprising a normally-collapsed pneumatic device having a passage to the 105
45 atmosphere and a member normally positioned by said weft detecting device to close said passage, said pneumatic device comprising a recessed disk, a diaphragm covering the recess, and connections from said 110
50 diaphragm to said weft replenishing mechanism.
5. In a loom, in combination, weft replenishing mechanism, a weft detecting device comprising a feeler slide and a detecting point, and means controlled by said weft detecting device effective to determine the 115
55 operation of said weft replenishing mechanism, said means comprising a normally-collapsed pneumatic device having a passage to the atmosphere, and a closure for said passage, said closure being mounted to move 120
60 with said detecting point relative to said slide to open said passage upon the substantial exhaustion of weft on the indicated weft carrier.
6. In a loom, in combination, weft replenishing mechanism, a weft detecting device, 125
65 comprising a feeler slide, a rod having a de-
- means controlling the operation of said weft replenishing mechanism, a spring to move said means to operative position, and a pneumatic device having a passage to the atmosphere, said pneumatic device being mounted 75
70 to move forward with the lay, and being effective to move said controlling means out of operative position if said passage remains closed during the forward movement of the lay.
7. A weft detecting device comprising a feeler slide, a detecting point carried by said slide and yieldingly movable therein, a pneumatic device connected to the weft replenishing mechanism and having a passage 80
85 to the atmosphere which constitutes the only opening to said device, and means movable with said detecting point and normally closing said passage to prevent the operation of said weft replenishing mechanism.
8. In a loom, a weft detecting device comprising a feeler slide, a rod having a detecting point supported on said slide, resilient means to hold said rod in rearward position relative to said slide, a pneumatic device connected to control the weft replenishing mechanism and having a passage to the atmosphere which constitutes the only opening 90
95 to said device, and a closure for said passage mounted on the forward end of said rod and normally moved by said resilient means into position to close said passage.
9. In a loom, in combination, weft replenishing mechanism, a weft detecting device, 100
100 and means controlled by said weft detecting device effective to determine the operation of said weft replenishing mechanism, said means comprising a normally-collapsed pneumatic device having a passage to the atmosphere and a member normally positioned by said weft detecting device to close said passage, said pneumatic device comprising a recessed disk, a diaphragm covering the recess, and connections from said 105
110 diaphragm to said weft replenishing mechanism.
10. In a loom, in combination, weft replenishing mechanism, a weft detecting device, an arm connected to control the operation of said weft replenishing mechanism, and means controlled by said weft detecting device effective to determine the actuation of said arm, said means comprising a movable recessed disk having a passage to the 115
120 atmosphere, a diaphragm covering the recess, and a device mounted on said diaphragm and engaging said arm, said weft detecting device having a member normally closing the passage in said disk and effective 125
125 to open said passage on the substantial exhaustion of weft on the indicated weft carrier.
11. In a loom, a weft detecting device comprising a feeler slide, a rod having a de-

tecting point supported on said slide, resilient means to hold said rod in rearward position relative to said slide, a pneumatic device movable with said slide and connected 5 to control the weft replenishing mechanism, said device having a passage to the atmosphere, and a closure for said passage adjustably mounted on the forward end of said rod and normally moved by said resili-

ent means into position to close said passage.

In testimony whereof I have hereunto set my hand, in the presence of two subscribing witnesses.

EPPA H. RYON.
